Primary Examiner — John Windmuller*Assistant Examiner* — John R Yeh(74) *Attorney, Agent, or Firm* — Guice Patents PLLC(57) **CLAIM**

The ornamental design for a pulsator for washing machine, as shown and described.

DESCRIPTION

FIG. 1 is a perspective view showing my new design for a pulsator for washing machine;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view showing the pulsator for washing machine in upside down position.

The broken lines are included for the purpose of illustrating portions of the structure that form no part of the claim.
